CLAIM

The ornamental design for a handle for a massage instrument, substantially as shown.

DESCRIPTION

FIG. 1 is a side elevational view of a handle for a massage instrument embodying my new design.

FIG. 2 is a side perspective view of the handle of a massage instrument.

FIG. 3 is a front elevational view thereof;

FIG. 4 is a rear elevational view thereof; and

FIG. 5 is a top plan view thereof.

*Fig. 1.**Fig. 3.**Fig. 2.**Fig. 4.**Fig. 5.*
